COLLAPSIBLE REEL

Robert C. Pierce, Niles, Mich., assignor to National-
Standard Company, a corporation of Delaware

Application August 17, 1953, Serial No. 374,499

6 Claims. (Cl. 242—124)

My present invention concerns reel constructions and more particularly a new and improved construction for a collapsible reel, particularly arranged and adapted for use as a let-off reel for wire and like materials.

By present practice, cable, wire, strapping material, etc. are shipped or transported in the form of annular coils from their place of manufacture to the consumer as opposed to past practice wherein such coils of wire were shipped mounted on a supporting reel made of wood or similar material. The expense of returning the empty reels to the wire maker after its consumption by the user led to uneconomical operation giving rise to the design and perfection of master reels for the coils which are retained by the consumer and reused to support additional coils of wire. One of the major problems in supporting such annular wire coils by a master supporting reel is encountered in the provision of sufficient tensioning or pressure on the ends of the reel to prevent knotting of the wire as it is withdrawn or laid off of the coil. Generally speaking, attempts of others in this field have resorted in elaborate spring systems for placing tension on the ends of the wire coil by forcing end plates of the reel axially toward one another; the wire coil being placed on a drum between such end plates. It is to this same general problem that the improved let-off reel of my present invention is directed.

It is believed that from the description of the improved device of my invention which follows its many advantages and features will be recognized readily and that its intents and purposes as outlined in the following listed objects will be appreciated.

The main object of my invention is to provide a new and improved collapsible let-off reel which employs pneumatic or hydraulic means for placing endwise compression on transportable coils of wire as they are supported on the reel.

Another object of my invention is to provide a new and improved reel construction embodying simplified means for placing constant endwise pressures upon wire coils supported on the reel thereby to prevent knotting and snarling of the wire as the same is let-off of the reel drum.

Still another object of my invention is to provide a new and improved collapsible let-off reel for supporting coils of wire, cable and the like which embodies certain improved and simplified features of construction which bring about a more efficient and reliable operation of the reel than has been heretofore experienced with presently known reels of this general class.

The above and further objects, features and advantages of my invention will be recognized by those familiar with this art from the description of its features as hereinafter set forth and with particular reference to the accompanying drawing.

In the drawing:

Figure 1 is a partial end elevational view of the reel of my invention with parts therein broken away to

demonstrate details of construction and particularly the features of the end plates for my collapsible reel; and

Figure 2 is a cross-sectional view taken substantially along line 2—2 of Figure 1 to illustrate the arrangement of its several elements and their embodiment in a workable organization.

Turning now to the drawings, it will be seen that the improved collapsible reel of my invention, indicated generally by numeral 10, comprises a pair of circular, metal reinforced wooden end plates 11 and 12, both similar in nature and design and arranged to be mounted in parallel spaced relation coaxially of a hub assembly, indicated generally at 13. Such end plates each have a plurality of radially disposed slotted openings 14, 14 extending inwardly of the plate's periphery for "strapping" a wire coil and further such are fitted with a continuous metal edge beading or tread 15 which promotes strength and durability.

The hub assembly 13 which supports the end plates 11 and 12 of my reel, comprises a tubular hub spindle 17 having a flange member 18 secured at one end thereof. Mounted over the end of spindle 17 opposite flange member 18 is a cylindrical hub collar 19 having screw threads 20 at its outer end. Hub collar 19 also has a flanged portion 21 to which a pin means 22 is fastened and extends between such flange and end plate 11 to prevent relative rotation between these parts. Pin 22 also acts as a convenient means for locating the end plate 11 in registration with end plate 12 so as to align the "strapping" slots 14 thereof. End plate 12 is affixed to the flange 18 of the hub spindle as by machine screws 23, 23 while the other end plate 11 is fitted coaxially of and radially about the sliding hub collar 19, intermediate the flanged portion 21 thereon and a lock nut 24 which engages with threads 20.

The hub spindle 13 further supports and is rigidly adjoined by set screws 27, 27 to a hub spider 28 having radially extending arm members 29 and a central cylindrical core portion 30. The hub spider further is provided with an enlarged circular or annular wall 31 at its one end (lower end as seen in Figure 2) which is fixed transversely to the separated arms 29 of the spider. Arms 29 are further cut away as at 32, to permit clearance of the hub collar flange 21.

Fixed at one end to the hub collar's flange portion 21 by means of pins 36 are three rod members 35, 35 which are disposed in symmetrically spaced array radially outward of the hub spindle 17 and the cylindrical core portion 30 of the hub spider. Rods 35 also prevent

rotation of collar 19 on spindle 17, but permit sliding movement of the collar relative to the spindle and vice versa. Such rods 35 invade or pass through the wall 31 of the hub spider via openings 37, 37 formed for such purpose. The other or unpinned end of each of the rod members is suitably threaded for receiving a lock nut 38 and further each rod is recessed suitably for receiving an annular snap ring 39.

It will be seen that a metal bearing plate 40, formed as an annular disc, is mounted over the threaded ends 60 of the three rod members 35 and locked thereto between the lock nuts 38 and the snap rings 39. Such bearing plate is moveable on spindle 17 and is spaced in parallelism with the annular wall portion 31 of the hub spider so as to provide an annular space 41 between such two members. Mounted intermediate end plate 12 and the bearing plate 40, coaxially and concentrically of the hub spindle 17 is a compression coil spring member 42 which serves as a resilient means for normally biasing the annular bearing plate and end plate 12 apart.

From the above arrangement of elements and their description, it will be appreciated that end plate 11 is loosely arranged about the hub collar member 19, but

is held thereon against axial disengagement by means of the hexagonal lock nut 24 and adjacent ends of spider arms 29. Nevertheless end plate 11 is free to slide coaxially of the hub collar intermediate the opposed faces of the lock nut and the adjacent ends of the spider arms 29. The hub collar 19 slides relative the spindle 17 and is connected by the rod members 35 to the bearing plate 40, which like end plate 11 is slidably moveable concentrically of and coaxially of the hub spindle 17; the same being held in parallelism with the two end plates by means of the lock nuts 38 and snap rings 39.

Conversely the hub spider 28 and the hub spindle 17 are tied rigidly together by screws 27 and further such members are tied to end plate 12 by flange 18 and screws 23. Further, it will be appreciated that the hub spindle, or that is the upper end portion thereof as illustrated in Figure 2, which is arranged concentrically inward of the hub collar 19, is slidably moveable relative to such hub collar and vice versa.

To provide means for moving the two end plates 11 and 12 toward one another I have devised a new and improved inflatable closed annulus or tube member 44 comprising rubber or like resilient material formed substantially similar to an inner tube familiarly used in pneumatic tires and having a valve means 45 similar to that employed for such tire inner tubes. Such valve means is rigidly connected as by a threaded lock ring 46 to the bearing plate 40 and outwardly of a washer member 47 with the valve stem portion 48 extending through the bearing plate. The annulus or tube member 44 is disposed intermediate the bearing plate 40 and wall portion 31 of the spider, or that is, it lies in space 41. By inflating the annulus the same moves axially of the reel to contact the adjacent or opposed faces of the bearing plate 40 and wall portion 31 of the spider forcing such two members apart. Since the bearing plate 40 connects to the hub collar 19 through the rod means 35, movement of such bearing plate downwardly, as seen in Figure 2, serves to pull the end plate 11 therewith and in a like direction. An outer position of end plate 11 is indicated in Figure 2 by broken lines, and its innermost position is shown by the full line. Similarly the wall portion 31 formed with the spider is joined to end plate 12 and is slidable with the hub spindle 17 relative to the hub collar 19. Thus, movement of the spider upwardly, as viewed in Figure 2, serves to pull the end plate 12 therewith in a like direction.

It will thus be recognized that inflation of the pneumatic annulus or tube serves to force the two end plates toward one another, compressing end-wise a coil of wire 49 disposed or mounted on a cylindrical core 50 supported around the spider. Such endwise compression of the coil of wire, as stated hereinabove, prevents tangling of the wire as the same is unlaid from its coiled condition. The amount of throw or axial movement of the two end plates relative to one another may be regulated to a certain extent by adjusting the lock nut 24 on the hub collar. Operating pressures for the annulus have been successfully employed up to approximately 80 pounds per square inch to give sizeable pressures end-wise of the reel of wire, thus serving to maintain a steady force thereon preventing tangling etc. as the wire is unlaid. Collapsing of the rubber tube or annulus 44 is carried out by releasing the pneumatic fluid therewithin through the valve means 45 and removal of the coil of wire or the placement thereof on the spider is accomplished by removing lock nut 24, and end plate 11 from the hub collar.

It will thus be appreciated and recognized that I have set forth the aspects and features of a new and improved collapsible reel embodying a pneumatic or fluid means for applying endwise pressure to a coil of wire carried by such reel. It will further be understood that while I have herein illustrated and described the features of my invention as related to a preferred embodiment thereof, several changes, modifications, and substitutions of equiva-

lents might be resorted to therein without departing from the spirit and scope of the invention involved. As a consequence, it is not my intention that I be limited to the specific form of my invention herein illustrated and described except as may appear in the following appended claims.

I claim:

1. A reel assembly of the class described, comprising in combination, a pair of spaced end plate members, a spindle means attached at one end to one of said end plate members, a collar member slidably mounted on the other end of said spindle member and attached to the other of said end plate members, a spider member mounted coaxially about said spindle member and fixed thereto between said end plate members, a planar wall formed at one end of said spider member and disposed in spaced parallelism with and between said two end plate members, a bearing plate connected to said collar member and disposed adjacently parallel said wall, but on the opposite side thereof from said other end plate member, said bearing plate being slidable coaxially of said spindle member; and an inflatable tubular annulus mounted between said bearing plate and wall and arranged when inflated to force the same apart and bias said two end plates simultaneously toward one another.

2. In a reel assembly of the class described, the combination comprising, a pair of circular end plate members, a spindle means mounted coaxially of said two plate members and attached at one end to one of said members, a collar member slidably mounted about the other end of said spindle member and attached to the other of said end plate members, a spider member mounted coaxially about said spindle member and affixed thereto, radially extending arm portions formed on said spider member for supporting an annular coil of wire intermediate said two end plate members, a planar wall portion formed at one end of said spider member and disposed in spaced parallelism intermediate said two end plate members, a bearing plate member slidably mounted coaxially and concentrically about said spindle member and attached to said collar member, and an inflatable rubber annulus mounted intermediate said wall said bearing plate being located on the opposite side of said wall portion from said collar member, and said bearing plate and arranged when inflated to bias said wall and bearing plate apart forcing said end plate members towards one another to securely grip and compress the ends of said coil of wire therebetween.

3. In a reel assembly of the class described, the combination comprising, a tubular spindle member, a first circular end plate member mounted transversely to said spindle member and at one end thereof, a collar member slidably mounted over the other end of said spindle member, a second end plate member removably mounted concentrically about and supported by said collar member, a spider member mounted between said end plate members and concentrically about said spindle member, means attaching said spider member rigidly to said spindle member, spaced arm portions on said spider member extending radially outward from said spindle member and adapted to support an annular coil of wire thereabout, a planar wall portion formed at one end of said spider member and disposed in spaced parallelism to and intermediate said two end plate members, an annular bearing plate member, slidably mounted concentrically on said spindle member and having attachment with said collar member, said wall portion being located between said collar member and said bearing plate member, an inflatable rubber annulus mounted intermediate said wall and said bearing plate member, and means for inflating said annulus thereby to bias said spider and said bearing plate members apart resulting in the coaxial movement of said end plate members toward one another to impose constant endwise compression on a coil of wire supported on the arm portions of said spider member.

4. In a reel assembly of the class described, the combination comprising, a tubular spindle member, a planar end plate member secured to one end of said spindle member, a collar member slidably mounted concentrically and coaxially on said spindle member and at the other end thereof, thread means formed on the exterior of said collar member, a second end plate member removably mounted on said collar member, the planes of the two end plate members being parallel, removable nut means locking said second end plate onto said collar member, a spider member mounted on said spindle member and intermediate said two end plate members, fastening means fixing said spider member to said spindle member, arm members formed integrally with and extending radially outward of said spindle member for supporting an annular coil of wire, a planar wall portion formed at one end of said arm members and disposed in spaced parallelism with and intermediate said two end plate members, an annular bearing plate mounted in spaced parallelism with said wall, means interconnecting said bearing plate with said collar member, said bearing plate being slidable relative to said spindle member, and an inflatable rubber annular tube mounted intermediate said bearing plate and wall and arranged when inflated to bias said two end plate members toward one another by forcing said spider and bearing plate apart thus to grip the coil of wire at its ends.

5. A reel assembly for supporting coils of wire and the like, comprising, an axial spindle, a pair of end plates, one fixedly attached to one end of said spindle and the other slidably attached to the opposite end of said spindle, a bearing plate means slidably mounted on said spindle in spaced parallelism to and between said two end plates, means attaching said bearing plate means to said other end plate for sliding movement therewith, a spider member defining a core support for a coil of wire, said spider member being affixed to said spindle and located between said bearing plate means and said other end plate, a planar wall member formed at one end of said spider and disposed in spaced parallelism adjacent to said bearing plate means, and an inflatable annulus mounted between said

bearing plate means and the said wall member of said spider, the arrangement being such that inflation of such annulus serves to separate said spider and bearing plate means and simultaneously pull said end plates toward one another to place a coil of wire supported therebetween under endwise compression, which compression persists throughout the unlaying of the wire coil.

6. A reel assembly of the class described, comprising, a spindle member, a hub collar slidably mounted over one end of said spindle member, a first circular end plate affixed transversely to the other end of said spindle member, a second end plate member removably mounted concentrically about said hub collar, a circular bearing plate, slidably mounted on said spindle between said end plates, rod members fixing said bearing plate in spaced parallelism to said second end plate, a spider member having radially extending spaced arms mounted on said spindle between said bearing plate and hub collar, said spider being fixedly attached to said spindle and movable therewith relative to said hub collar and bearing plate; the radial extent of said arms thereof defining support means for a cylindrical coil of wire to be supported between said end plate, spring means resiliently thrusting said bearing plate toward an adjacent end of said spider, and an inflatable annulus mounted between said bearing plate and said spider to force the same apart when inflated, this action serving to move said end plates toward each other to place the said coil of wire therebetween under constant endwise compression, the said end plates following lengthwise alterations of the wire coil as the same is unwound.
